Specification of Letters Patent. Patented Feb. 28, 1922.

Application filed September 29, 1920. Serial No. 413,577.

To all whom it may concern:

Be it known that I, EMIL CLEMENS HORST, a citizen of the United States, residing at the city and county of San Francisco and State of California, have invented a new and useful Improvement in Separators, of which the following is a specification.

This invention relates to a separator and especially to a machine for separating leaves, petals, stems, etc., from hops and the like.

Picking of hops by machinery is resorted to at the present time in several of the larger hop growing districts, and is becoming more and more a necessity, due to the scarcity of labor and other troubles connected with the industry. Hops picked by machinery will, as a rule, contain a considerable quantity of leaves, petals, stems and other foreign matter; the major portion of which is removed by separators of various types. It happens however that most of the separators employed are not capable of thoroughly separating the hops. For instance one type of separator may be fairly efficient for removing leaves and petals, while another type may be fairly efficient for removing stems or similar material. It is therefore more or less common practice to pass the hops through two or more separating operations before they are considered sufficiently clean to be dried and baled.

One of the objects of the present invention is to provide a simple and easily operated separator, which is capable of efficiently removing both stems, leaves and petals.

Another object of the invention is to provide a separator which consists of two distinct separating units, one of said units consisting of an inclined continuously travelling belt for the removal of leaves, petals, stems, etc., and a second unit consisting of a series of deflectors capable of removing the major portion of the sound hops, said second unit being placed above the first unit or the belt and receiving the hops to be cleaned. All the hops are therefore received on the first unit and as the major portion of the clean hops are removed by deflector action, it is obvious that the secondary unit or the belt is subjected to a comparatively small volume of hops when in operation.

Another object of the invention is to pro-

vide means for imparting a vibratory movement to the deflecting unit to increase the efficiency of the deflectors and to automatically remove stems, leaves, petals, etc., which may have a tendency to lodge upon the deflectors.

Further objects will hereinafter appear.

The invention consists of the parts and the construction, combination and arrangement of parts, as hereinafter more fully described and claimed, having reference to the accompanying drawings, in which—

Fig. 1 is a side elevation in section showing the position of the two separating units.

Fig. 2 is a front view of the separator.

Referring to the drawings in detail, A indicates a frame of suitable construction in which is journalled a pair of shafts 2 and 3. These shafts are separated and the shaft 2 is placed above the shaft 3 so that a belt 4 supported thereby may assume an inclined position as shown. Any suitable form of belt may be employed. For instance a belt constructed of canvas, rubber or the like. The belt employed in the present instance is attached to cross slats 5 in a manner similar to a draper belt. These cross slats are in turn secured to sprocket chains 6, disposed on opposite sides of the belt, and the chains are in turn supported by sprocket gears 7 secured on the shafts 2 and 3, respectively, there being of course two pair of interspaced sprocket gears on each shaft.

Extending crosswise of the main frame is a shaft 8, and pivotally supported by the shaft is a pair of interspaced side bars 9 which are connected by means of jumper plates or deflectors 10, of which there are a suitable number, depending upon the size of the separator. The side bars 9 are slotted longitudinally as at 11, and each deflector is provided with a pair of end bolts 12, which extend through the slotted portions 11 of the side bars. These bolts are tightened when the deflectors are in position by means of nuts 14, as the outer ends of the bolts 12 are threaded and they therefore permit adjustment of the individual deflectors, first in regard to spacing, and secondly as to the incline presented. The side bars 9 are disposed above the main separating belt 4, and consequently the deflecting plates 10. These plates are provided for

the purpose of disposing of the major portion of the hops delivered to the machine, or in other words for the purpose of relieving the main separating belt of congestion as will hereinafter be described.

The lower ends of the side bars are provided with shoes or striker plates 15, which are engaged by cams 16. These cams are disposed one on each end of the shaft 3 in alignment with the side bars and will, during the revolution of the shafts 2 and 3, intermittently raise the side bars in unison and thereby impart a vibratory or intermittent drop movement to the deflecting plates 10, that is the shoes 15 engaged by the cams are raised comparatively slowly, but are permitted to drop rapidly by gravity, due to the shape of the cams, the cams employed being similar to those used in stamp

10 mills, etc.

15 The lower ends of the side bars are provided with shoes or striker plates 15, which are engaged by cams 16. These cams are disposed one on each end of the shaft 3 in alignment with the side bars and will, during the revolution of the shafts 2 and 3, intermittently raise the side bars in unison and thereby impart a vibratory or intermittent drop movement to the deflecting plates 10, that is the shoes 15 engaged by the cams are raised comparatively slowly, but are permitted to drop rapidly by gravity, due to the shape of the cams, the cams employed being similar to those used in stamp

20 mills, etc.

25 The hops to be separated or cleaned are delivered to the machine by a feed conveyor 17 of suitable construction. The clean hops are removed from the machine by a clean hop conveyor 18 and the leaves, petals, stems, etc., by a discharge conveyor 19. All the conveyors employed are of the endless belt type and may be suitably arranged and driven, similarly power may be transmitted 30 to drive the main separating belt in any suitable manner or as here shown by a pulley 20. The operation of the machine will be as follows:

35 The main feed conveyor 17 is positioned slightly above the first deflecting plate 10 carried by the side bars 9. The hops delivered by the conveyor drop downwardly on the first deflecting plate and as this is slightly inclined as shown, it can be seen 40 that the major portion of the hops will bounce off the plate to the second and third plate and so on, until they are deposited upon the clean hop conveyor 18. Hops are rather resilient, due to the formation or 45 growth of the same and have a decided bouncing or jumping action when dropped upon a deflecting surface, this peculiar tendency has been taken advantage of to remove the major portion of the sound hops before 50 or without subjecting the same to the action of the main separator belt 4. In other words, comparatively all sound hops are disposed of without overburdening or congesting the main separator belt. A small portion of the hops will, however, drop downwardly between the deflecting plates and 55 lodge upon the inclined surface of the upwardly travelling belt 4. All sound hops encountering the belt will jump and roll in 60 a downward direction and will finally be delivered to the clean hop conveyor 18, while leaves, stems, petals or other foreign material delivered upon the belt, will adhere thereto and will be delivered to the discharge conveyor 19. A considerable quan-

65 tity of petals, leaves, etc., will also lodge upon the deflecting plates 10, but as the plates are constantly subjected to a vibratory movement, it is obvious that the leaves and other matter will slide off the plates and 70 will drop between the same and finally lodge upon the belt, which will deliver all the foreign material to the main discharge conveyor.

75 In actual practice I find that the separating action is ideal as all sound hops are disposed of without subjecting the same to the action of the main separating belt. The major portion of the stems, leaves and petals are subjected to two separating actions, first 80 because the major portion lodges upon the deflecting plates, and secondly, because this material is subjected to a second separating action when deposited upon the main belt. The capacity of the machine is more than 85 double, due to the two distinct separating actions taking place and a cleaner product is obtained. Subjecting the hops to two or more separating actions in separate machines is also obviated and the cost of handling 90 similarly reduced.

95 While a more or less specific structure is shown, I wish it understood that various changes in form and proportion may be resorted to within the scope of the appended claims, similarly that the materials and finish of the several parts employed may be such as the experience and judgment of the manufacturer may dictate or varying uses 100 may demand.

Having thus described my invention, what I claim and desire to secure by Letters Patent is—

1. In a separator of the character described the combination with the main separating belt of a pair of side bars pivotally supported at one end above the belt, deflecting plates secured between the side bars, a pair of cam members engageable with the free end of the side bars and adapted to impart a vibratory movement thereto.

105 2. In a separator of the character described the combination with the main separating belt of a pair of cam members rotating in unison therewith, a pair of side bars disposed above the belt, a shaft on which said bars are pivotally mounted, said cams supporting the lower ends of the side bars and imparting a vibratory movement thereto, and deflector plates secured between 110 the side bars.

115 3. In a separator of the character described the combination with the main separating belt of a pair of cam members rotating in unison therewith, a pair of side bars disposed above the belt, a shaft on which said bars are pivotally mounted, said cams supporting the lower ends of the side bars and imparting a vibratory movement 125 thereto, deflector plates secured between the 130

side bars, and means permitting separation of the deflecting plates and adjustment of the individual plates to present varying angles.

5 4. A hop separator comprising a main frame, a pair of shafts journaled in the frame, an endless upwardly travelling inclined belt supported by said shafts, a pair of side bars disposed above the belt, a pivotal mounting at the upper ends of the bars supporting the same, a pair of cam members on one of the shafts supporting the lower ends of the side bars and imparting a vibratory movement thereto, a longitudinally extending slot formed in each side bar, a series of superposed deflecting plates disposed between the side bars and a fastening member at each end of each deflecting plate permitting angular adjustment 15 of the individual deflecting plates and separation of the same.

5 5. A separator comprising an endless belt, a pair of side frames pivotally supported at one end above the belt, means engaging the lower ends of the side frames for imparting vibratory movement thereto, and a series 25 of adjustable deflector plates supported by the side frames.

6. A separator comprising an endless belt, means for transmitting motion thereto, a pair of side bars pivotally supported at one end above the belt, a longitudinally extending slot formed in each side frame, a series of deflecting plates having projections engaging the slots in the side frames for adjustably supporting the plates, and means 30 35 engaging the free end of the side frames for imparting vibratory movement thereto.

7. In combination with an endless travelling belt and delivery and discharge mechanism associated therewith, of a series of adjustable deflecting plates, a frame adapted to support the same, the said frame pivotally supported at one end, and means operated 40 in unison with the endless belt and engageable with the free end of the frame for imparting oscillating movement to said frame.

In testimony whereof I have hereunto set my hand in the presence of two subscribing witnesses.

EMIL CLEMENS HORST.
